Patented Dec. 12, 1922.

UNITED STATES PATENT OFFICE.

HARRY A. NUTTER, OF SEYMOUR, INDIANA.

EXPANSION-SOCKET WRENCH.

Application filed April 25, 1922. Serial No. 556,432.

To all whom it may concern:

Be it known that I, HARRY A. NUTTER, a citizen of the United States, and a resident of Seymour, in the county of Jackson and 5 State of Indiana, have invented certain new and useful Improvements in Expansion-Socket Wrenches, of which the following is a full, clear, and exact description.

My invention relates to expansion socket 10 wrenches, and one of the objects of the invention is to provide a device of this character which also securely hold bits or other tools of various sizes.

Another object of the invention is to provide 15 a device of this character which is adapted to be used with brace or drill sockets of various sizes.

A further purpose of the invention is to provide a device of this character which is 20 not only strong and durable, but also is simple in construction and inexpensive in manufacture.

Other and further objects and advantages 25 of the invention will be apparent to those skilled in the art from the following detailed description, when taken in connection with the accompanying drawings, in which:

Figure 1 is a side elevation of the completed device, the resilient arms being closed 30 to their full extent.

Figure 2 is a longitudinal sectional view through the device, the resilient arms being closed to their full extent.

Figure 3 is a vertical transverse sectional 35 view taken on line 3—3 of Figure 2.

Figure 4 is a detail view of the gripping member carrying the resilient arms, the clamping sleeve being indicated in dotted lines; and

40 Figure 5 is a fragmentary perspective view of the gripping member and one of the resilient arms, the gripping member being in section.

Referring to the drawings more in detail, 45 numeral 1 indicates a body member which is screw threaded for a portion of its length, and screw threadedly engaged therewith is a clamping sleeve 2.

A gripping member 3 has a projection 4 50 thereon, and the projection screw threadedly engages the wall of a recess provided in the body member. Further means for attaching the gripping member to the body member and for preventing relative rotation between 55 the two members consists of a lock-screw 5

which screw threadedly engages the body member and the gripping member; lock-nuts 6 being disposed on the end of the lock-screw.

The gripping member is shown as carrying 60 four resilient arms indicated by numeral 7. These arms, when not restrained, spring outwardly to the position shown in Figure 4. While I have shown four of the resilient arms, it will be understood, of 65 course, that a greater or lesser number may be employed. On the end of each resilient arm is a jaw 8, and each jaw is provided with a right angular channel 9.

The operation of the apparatus thus far 70 described is as follows:

By rotating the clamping member to move it to the left (Figure 2) the spring arms 7 are released and automatically spring outwardly. A bit or other tool is then placed 75 in the jaws carried by the resilient arms and the clamping sleeve is rotated to carry it to the right (Figure 2), whereby the clamping sleeve engages the resilient arms, forcing 80 them towards each other, and the jaws grip the bit or other tool and hold it firmly.

The body member 1 is also recessed at the opposite end and the wall of said recess is screw threaded, as indicated by numeral 10. An adjustable holder 11 has a projection 12 85 which is screw threadedly engaged in the recess and locked therein by means of the lock-screw 13. The holder is rendered adjustable by means of being split, as indicated by numeral 14, and a wing 15 is provided on the holder on each side of the slot. An adjusting screw 16 engages the wings 90 and clamps the holder on the brace or drill socket member. It is thus apparent that the device may be clamped on brace or drill 95 socket members of various sizes.

From the foregoing detailed description it will be obvious that I have invented an expansion socket wrench which possesses numerous advantages over similar expansion 100 socket wrenches previously known.

In accordance with the the patent statutes, I have described what I now believe to be the best embodiment of the invention, but I do not wish to be understood thereby as 105 limiting myself or the scope of the invention, as many changes and modifications may be made without departing from the spirit of the invention; all such I aim to include in the scope of the appended claims. 110

What I claim as new and desire to secure by Letters Patent is:

1. A device of the character described, including a body member, an adjustable holder screw threadedly mounted on one end thereof, and a gripping member screw threadedly mounted on the other end thereof, resilient arms carried by the gripping member, jaws carried by the resilient arms, 10 and a clamping sleeve screw threadedly mounted on said body member and engaging the resilient arms.
2. A device of the character described, including a body member provided with a recess in each end thereof, an adjustable holder screw threadedly mounted in one of said recesses, and a gripping member screw threadedly mounted in the other of said recesses, resilient arms carried by the grip-

ping member, jaws carried by the resilient 20 arms, and a clamping sleeve screw threadedly mounted on the body member and engaging the resilient arms.

3. A device of the character described, including a body member provided with a 25 recess in each end thereof, an adjustable holder screw threadedly mounted in one of said recesses, and a gripping member screw threadedly mounted in the other of said 30 recesses, a lock screw engaging the body member and the gripping member, a lock nut provided on the lock screw, resilient arms carried by the gripping member, jaws carried by the resilient arms, and a clamping 35 sleeve screw threadedly mounted on the body member and engaging the resilient arms.

HARRY A. NUTTER.
